UNITED STATES PATENT OFFICE.

EDWIN E. ARNOLD, OF PITTSBURGH, PENNSYLVANIA, ASSIGNOR TO WESTINGHOUSE ELECTRIC & MANUFACTURING COMPANY, A CORPORATION OF PENNSYLVANIA.

IRONING MACHINE.

Application filed December 23, 1921. Serial No. 524,532.

This invention relates to ironing machines and has for an object to produce a machine which is more effective for the purposes intended and is easier to operate than other machines now in use and known to me.

The ordinary domestic ironing machines consist of a stationary iron and a rotating padded roll. The roll is ordinarily so arranged that it is pressed against the iron 10 while rotating and is moved away from the iron for the purpose of adjusting articles to be ironed or for the purpose of releasing articles in the process of being ironed. Such machines are usually so arranged that rotation of the padded roll is stopped when the roll is moved away from the iron. In some machines, the movement of the roll toward and away from the iron is accomplished by hand, whereas in others the roll 15 is held against the iron by foot pressure exerted through the agency of a pedal. In either case considerable effort is expended by the operator during the ironing operation.

An object of my invention is to produce 25 an ironing machine in which motor-driven means under the control of the operator are employed for the purpose of shifting the position of the padded roll with relation to the iron.

30 A further object is to produce a more effective iron for domestic ironing machines than those now in use and known to me.

A still further object is to produce an ironing machine in which automatic means 35 are employed for regulating the temperature of the iron.

40 A further object is to produce a machine employing a thermostatic heat regulating mechanism in which simple and effective means are employed for varying the adjustment of the thermostatic mechanism for the purpose of varying the temperature of the iron at the will of the operator.

45 These and other objects which will be made more apparent throughout the further description of my invention are attained by means of apparatus herein described and illustrated in the drawings accompanying and forming a part hereof.

50 In the drawings, Figure 1 is a side elevation of an ironing machine embodying my invention, portions being shown in section for convenience of illustration. Fig. 2 is a fragmental sectional elevation of the machine shown in Fig. 1, and illustrates the

mechanism employed for rotating the roll and for shifting the relative position of the roll and iron. Fig. 3 is a sectional view along the line 3—3 of Fig. 2. Fig. 4 is a fragmental rear view of an iron embodying my invention shown in connection with thermostatically controlled mechanism for delivering fuel to the burner associated with the iron; a portion of the back plate of the iron is shown broken away and removed and a portion of the thermostatically controlled mechanism is shown in section for convenience of illustration. Fig. 5 is a detail view of a portion of the apparatus shown in Figure 5. Fig. 6 is an end view of the iron shown in Fig. 4, associated with a diagrammatic representation of a roll. Fig. 7 is an intermediate transverse section of the iron shown in Fig. 4 associated with a diagrammatic representation of a roll. Fig. 8 is a section through a modified form of ironing shoe showing an electric, thermostatically controlled heating mechanism.

Referring to the drawings, the iron 7 is of the usual external appearance and is rigidly mounted on the frame 8 of the machine. A padded roll 9 is mounted on links 10 in such a way that it is capable of being rotated and also of being swung toward and away from the iron without throwing its operating gears out of engagement. As shown, the links 10 are pivotally mounted on a shaft 11 which forms a part of the operating mechanism and extends longitudinally of the roll 9. The roll is provided with the usual trunnions which are journaled in the upper ends of the links. The roll is rotated by means of a driving gear 12 rigidly mounted thereon and concentric therewith. A driving pinion 13 rotatably mounted on the shaft 11 meshes with and drives the gear 12. The axis of the pinion 13 coincides with the pivotal axis of the links 10, consequently, the gear 12 rolls around the pinion 13 during the operation of swinging the roll toward and away from the iron and the gear 12 is always in mesh with the pinion.

Power is applied to the pinion 13 by means of a worm 14, a worm wheel 15, and a clutch 16. As shown in Fig. 3, the worm wheel 15 is splined on a sleeve 17 which is loosely mounted on the shaft 11 and is adapted to be moved to different longitudinal positions along the shaft by means of a finger 18. One end of the sleeve 17 is

shown provided with a clutch member such as teeth which co-operate with correspondingly formed teeth on the boss of the pinion 13 to form the clutch 16. The other end 5 of the sleeve is provided with a clutch member such as teeth which co-operate with similarly formed teeth on a collar 20, rigidly mounted on the shaft 11, to form a clutch 19. With this arrangement the worm wheel 10 15 will drive the pinion 13 or the shaft 11, depending upon the longitudinal position of the sleeve 17 on the shaft 11. When the sleeve 17 is in the position shown in Fig. 3, in which the clutch 16 is effective, the worm 15 wheel 15 is operatively connected to the pinion 13 and is therefore effective in rotating the roll 9. When the sleeve 17 is moved to a position such that the clutch 19 is rendered effective, the worm wheel 15 is 20 no longer capable of transmitting power to the pinion 13 but drives the shaft 11, since it is operatively coupled to that shaft through the agency of the sleeve 17, the clutch 19 and the collar 20.

25 The finger 18 is preferably bifurcated at its outer end to form a yoke which engages a groove formed in the sleeve 17. As shown in Fig. 3, it is mounted on a longitudinally shiftable bar 21 which may be controlled by 30 a pedal 22 (Fig. 1) through the agency of a flexible connection 23 and a motion reversing lever 24, the arrangement being such that when the pedal is depressed, the finger 18 is shifted to a position which moves the sleeve 35 17 out of operative engagement with the pinion 13 and into operative engagement with the collar 20. As shown, the bar 21 is mounted in suitable bearings carried by the frame 8 and is normally held in a position 40 such that the sleeve 17 is operatively connected to the gear 13 through the agency of the clutch 16. This is accomplished, in the illustrated embodiment by means of a coil spring 25, which surrounds the bar and is 45 located between one bearing block of the bar and a collar 27 rigidly secured to the bar. The finger 18 is yieldingly held against the collar 27 by means of a coil spring 28 which operates between the boss of the finger and 50 a collar 29 rigidly secured to the bar.

The shaft 11 carries an element such as 55 cam member or disc 30 which operates to swing the roll toward and away from the iron. The operation of the cam member 30 is manually controlled through the agency of the pedal 22 and the bar 21. This member 30 is rigidly mounted on the shaft 11 and rotates with it when the sleeve 17 is 60 operatively coupled to the collar 20. Any means such as a crank pin and connecting rod may be employed for imparting swinging motion from this disc 30 to the roll 9, but as shown pin 31 is mounted on the disc 30 and performs the function of a crank pin 65 in that it shifts the position of a bell crank

32 pivotally mounted on the frame 8, as the disc 30 revolves with the shaft 11. As shown, the pin 31 projects through a slot formed in one end of the bell crank 32 and the oscillatory motion of the bell crank is 70 imparted to it by this pin-and-slot connection. The other end of the bell crank operates to swing the roll 9 about its pivotal support. In the apparatus illustrated, this is accomplished by means of a coil spring 33 75 which operates between the free end of the bell crank and the upper end of the link 10. As shown, a spring block 34 is pivotally connected to the free end of the bell-crank and a similar spring block 35 is pivotally 80 connected to the swinging end of the link 10. The spring 33 is so formed and so mounted on the spring blocks 34 and 35 that it is capable of operating as a tension spring for the purpose of yieldingly holding the roll 85 9 against the iron or as a strut for the purpose of moving the roll away from the iron. As the cam member 30 turns from the position shown in Fig. 1, the lower end of the bell crank is depressed by the action of the 90 pin 31 in the slot of the bell crank. This movement of the bell crank first relieves the tension of the spring 33 and then shifts the roller 9 away from the iron by causing the spring 33 to operate as a strut.

95 In addition to shifting the sleeve 17 the bar 21 also performs the function of a cam lock bar in that it cooperates with the cam member 30 in such a way as to lock that member in determined positions and on the other hand the cam member automatically controls the shifting of the bar in response to the pressure of the coil spring 25. As shown, the member 30 is provided with a notch 36 located adjacent the periphery thereof. A slot 37 diametrically opposed to the notch 36 is also formed in the member 30. The notch is adapted to engage the projecting end of the bar 21 and to hold the bar in an intermediate position in which the 100 clutch members 16 and 19 are both rendered inoperative so that the rotation of the worm wheel 15 neither transmits power to the pinion 13 nor to the shaft 11. This notch 105 is also so located with relation to the pin 31 110 on the cam member 30 that when it is in engagement with the bar 21, the roll 9 is held in the extreme position away from the iron. The slot 37 is so located with relation to the pin 30 that when it is in engagement with 115 the bar 21, and the roll 9 is held in ironing contact with the iron. In addition, the slot 37 permits the bar 21 to move to the extreme position in response to the pressure of the spring 25 and to thereby render the 120 clutch 16 effective in operatively connecting the worm wheel and the pinion 13.

125 When it is desired to stop the roll 9 and to move it out of engagement with the iron, the pedal 22 is momentarily depressed an 13

amount sufficient to withdraw the end of the shaft 21 from engagement with the cam member 30. This movement of the bar first releases the clutch 16 and then operatively couples the sleeve 17 to the collar 20 by rendering the clutch 19 effective and the worm wheel to drive the shaft 11. As soon as the worm wheel is operatively coupled to the shaft 11, the cam member 30, in rotating in response to the rotation of the shaft 11, moves the slot 37 out of line with the end of the bar and thereby prevents the end of the bar 21 from again entering the slot and holds the bar in the extreme position in which the worm wheel is operatively coupled to the shaft 11. Under these circumstances, the cam member 30 continues to rotate until the notch 36 moves under the cam bar 21 which has, during the rotation of the member 30, been yieldingly pressed into engagement with the lateral face of the member by the spring 25. As soon as the end of the cam bar drops into the notch 36 the shaft 11 ceases to rotate since the clutch 19 is rendered ineffective as a power transmitting element, and the cam member is held stationary by the engagement of the bar 21 with the notch 36. Incidentally, the movement of the cam 30 from the position in which the slot 37 is engaged by the cam bar to the position in which the notch 36 is engaged by the bar swings the roll 9 away from the iron through the agency of the bell crank 32. When it is desired to move the roll 9 back into engagement with the iron and to cause it to rotate, the pedal 23 is momentarily depressed, thereby withdrawing the cam bar from the notch 36 and locking the sleeve 17 to the collar 20. This causes the cam member to rotate, moving the notch 36 out of line with the end of the bar 21 and consequently prevents the bar from moving back in response to the pressure of the spring 25. The motion of the cam member continues until the end of the bar 21 drops into the notch 37, and thereby shifts the sleeve 17 through the neutral position to the extreme position in which the clutch 16 is rendered operative. During this movement of the cam member, the bell crank 32 is shifted so as to move the roll 9 into engagement with the iron and subject the spring 33 to strain.

It will, of course, be apparent that each end of the roll 9 is provided with a bell crank 32 and spring 33, so that the pressure of the roll against the iron and the swing of the roll is uniform throughout the length of the roll. It is, of course, unnecessary to duplicate the cam lock bar 21 and the associated notch 36 and slot 37 but a disc carrying a pin 31, such as shown in Figures 1 and 2, is preferably employed at the other end of the roll and the pin operates the bell crank

32 at that end of the machine. This disc is mounted on the shaft 11.

It will also be apparent that suitable bearings are provided for the shaft 11 and that the pivoted ends of the links 10 may be provided with rigid supports or bearings for the purpose of relieving the overhung portion of the shaft 11 of the strains occasioned by the roll 9. It will also be apparent that some means such as stationary abutments secured to the frame 8 may be employed for preventing longitudinal movement of the worm wheel 15.

In the drawings, I have shown the sleeve 17 journaled in a bearing ring 38 which is rigidly supported on the frame 8 and which also forms an abutment for holding the worm wheel 15 in place. The worm wheel is shown provided with a laterally projecting hub which engages a lateral face of the gear 13, whereas the gear 13 is held in position by the link 10 and the cam member 30 which, as previously described, is rigidly mounted on the shaft 11.

The iron illustrated as an embodiment of the present invention is provided with an ironing surface 40 which extends throughout the length of the padded roll 9 and conforms more or less to the contour of the surface of the roll 9 engaged by it. In ironing dampened articles the drying action and consequently the effectiveness of the ironing is occasioned by the fact that the water or moisture carried by the articles is almost immediately converted into steam on being subjected to the heat of the iron. It will be apparent that the ironing operation will be rendered more effective if means are provided for venting the steam or vapor thus formed. In my improved iron, I form the ironing surface, or the surface of the iron adjacent to the roll, so that the steam and vapor is vented to the atmosphere immediately after its formation. In this respect, my iron differs from irons ordinarily employed in connection with domestic mangles since, in such machines, the ironing surface subtends a relatively large arc of the padded roll and is held, more or less, firmly into engagement with the surface of the material or articles ironed by the pressure of the roll. I provide a depression in the ironing surface which is so located and arranged that the material passing across the iron is gradually relieved of the pressure of the roll as it moves past the depression and is simultaneously moved into an area which is in free and open communication with the atmosphere through one or more vent passages.

In the iron illustrated, I have provided a depression 41 in the face of the iron adjacent the roll 9, and I have provided slots 42 through the iron at a point adjacent the apex of the depression. These slots are pref-

erably narrow and extend in the direction of rotation of the roller and are preferably spaced apart a distance substantially equal to their width. The series of slots preferably extends from one end of the iron to the other parallel to the axis of the roll 9, and establishes communication between the ironing surface of the iron and a longitudinally extending chamber 43 which is vented 5 to the atmosphere by one or more passages 44 which extend through the heating chamber of the iron and the cover plate 45 or rear wall of that chamber. The chamber 43 may be relatively shallow but is of sufficient 10 volumetric capacity to readily convey the steam or vapor, liberated from the material or articles ironed, to the vent passages 44 without building up pressures by reason of frictional resistance to flow. It will, of course, be understood that the depression 41 is so formed that shoulders or edges are avoided on the ironing surface of the iron and its depth is not sufficient to permit buttons to assume a cross-wise position or to 20 cause articles ironed to pile up or become wrinkled in passing it. The principal function of the depression is to relieve or partially relieve the articles ironed of the full ironing pressure and at the same time provide a vent for steam or vapor which may be carried by them. The depression is preferably formed intermediate the inlet and outlet edges of the ironing surface so that articles or material moving with the roll is again subjected to full ironing pressure after 30 passing the depression.

The heating chamber of the iron is substantially similar to irons now in use. An elongated burner 46 extends throughout the 40 length of the iron and is located near the bottom of the heating chamber which is enclosed between the ironing surface 40 and the back cover 45. I preferably employ heat transmitting ribs 47 on the rear face 45 of the iron. This is for the purpose of increasing the heat absorbing area of the iron and thereby rendering the iron more effective as a heat conveying and transferring agent. As shown, these webs or 50 ribs are located near the top of the iron or at a point where it is desirable to support the subject the articles to be ironed to the greatest quantity of heat. The ribs may be spaced and proportioned so as to give the best results from the standpoint of maximum heat conductivity.

Another feature of my invention is to provide automatic means for controlling the temperature of the iron. This is accomplished in the apparatus illustrated by thermostatically controlling the operation of the fuel delivery valve in such a way as to maintain a maximum temperature at a point of the iron immediately adjacent to the receiving edge thereof.

As shown in the drawings, I provide a cored notch or passage 48 in the iron proper at a point adjacent its upper edge. This notch or passage preferably extends the entire length of the iron and is adapted to receive a thermostatic element such as a brass or bronze bar 49 having a different coefficient of expansion from that of the material of which the iron proper is formed. As shown, one end of the bar is rigidly secured to one 70 end of the iron proper, whereas the other end of the bar projects beyond the other end of the iron proper so as to form a connection which may be employed in operating the fuel valve. In Fig. 4, a bracket 50 is 75 shown rigidly secured to the end of the iron 40 and forms a support for a bell crank 51. The bell crank is pivotally mounted on the bracket 50 and besides imparting the motion occasioned by the difference in expansion or contraction of the iron proper and the thermostatic element 49 to the valve, it also performs the function of a motion-multiplying device. For this reason the arm of the bell crank operatively coupled to the 80 valve 52 is considerably longer than the arm operatively coupled to the element 49. As shown, a knife-edge connection is provided between the bell crank and the element 49 and lost motion between these two members 85 is prevented or taken up by a spring 53. The element 49 carries the knife edges on a collar 54 and is provided with an extension 55 of reduced diameter which is threaded at its outer end to receive a spring retaining 90 and adjusting nut. A coil spring surrounds the extension 55 and is located between the nut carried thereby and the bifurcated end of the bell crank which engages the knife edges. A similar construction is employed 95 between the longer arm of the bell crank and the element employed for operatively connecting it to the valve 52. As shown in Fig. 4, the valve is of the plug or needle valve type and cooperates with a valve casting 56 having the usual inlet and outlet port and the usual valve seat formed in the diaphragm.

The valve is shown provided with an integrally-formed squared head 57 which is 100 drilled and tapped to receive the threaded end of a rod or link 58. The head 57 is located in a squared aperture 59 formed in an adjustable disc 60, the arrangement being such that the head may be moved to different positions with relation to the disc 60 for the purpose of moving the valve 52 toward or away from the valve seat. As shown, the disc is provided with a cylindrical extension located on one side thereof concentric 105 with the aperture 58 and adapted to extend into a corresponding socket formed in the head of the valve casting 56. With this arrangement the disc 60 may be turned to different positions for the purpose of changing 110

the relative adjustment between the head 57 and the link 58. In order to accomplish this conveniently, I have shown the disc provided with a handle 61. It will be apparent that variations in the relative adjustment between the head 57 and the link 58 will vary the operation of the valve in response to the operation of the thermostatic elements and that an adjustment of the disc which will, in effect shorten the valve stem and adjust the thermostatic elements so that they will not close off the fuel supply until higher temperature has been attained; likewise an adjustment of the disc which will, in effect lengthen the valve stem, will occasion a closing of the valve in response to a lower temperature. In order to calibrate the adjustment of the disc, I provide a segment 62 on the valve casing and a cooperating pointer 63 on the disc. The segment may be calibrated in degrees and may be employed in setting the apparatus to maintaining the desired temperature of the iron. It will, of course, be understood that any convenient means may be employed for holding the disc in place on the valve casing and at the same time permitting it to rotate relatively thereto. As shown, the link is provided with an adjustable nut or collar 68 and a coiled spring 58^a is located between the collar and the disc 60.

In the illustrated embodiment the link 58 is provided with an extension 64 which projects through an elongated slot in the end of the bell crank 51. A head 65 is rigidly secured to the upper end of this extension and is provided with knife edges which engage the bell crank arm on opposite sides of the extension. In order to maintain the adjustment between the knife edges and the bell crank arm I have provided the bell crank arm with a relatively shallow V-shaped groove which is engaged by the knife edges. The lost motion between the link 58 and the bell crank is taken up or prevented by coil spring 66 which surrounds the extension 64 and operates between a collar 67 formed on the link and the lower face of the bell crank arm. The extension 64 is preferably so formed that it will yield readily to cross bending and at the same time it is preferably so fitted into the elongated slot of the bell crank arm that it prevents the link from turning when the disc 60 is rotated to vary the adjustment to the valve. Lost motion between the link 58 and the head 57 is taken up by a coil spring 69 located between the head and the adjustable collar 68 on the link.

In order to prevent the valve 52 from completely closing off the fuel supply to the burner 46, I preferably provide a restricted orifice 70 in the diaphragm of the valve which is so proportioned that it will permit a sufficient quantity of fuel to pass

to the burner to prevent the flame at the burner from going out even when the valve is closed. It will be apparent that the springs 53, 66 and 58^a will prevent injury to the valve or the valve set due to continued differential expansion of the thermostatic elements after the valve is closed.

In Figure 8 I have shown a thermostatic device for controlling the flow of current to an electric heater *a*, with which the iron is equipped.

The thermostatic element 49 *b* is secured at one end to the iron and projects at the other end as described in connection with the apparatus illustrated in Figure 4. The differential expansion of this element, with relation to the iron, is employed for varying the current flow through the heater. In the drawing I have provided the carbon disc pile *c* located in an insulating support *d* and connected into the circuit heater. The lever *e* pivotally mounted on the iron is actuated by the rod 49 *b* to vary the pressure on the pile *c* and to thereby vary the current flow.

As shown the upper end of the lever projects into a slot provided in the rod and is engaged by an adjusting screw *f*. A spring *g* is so located between the lever and the rod that the lever is yieldingly pressed into an engagement with the screw *f*. A heavy coil spring *h* operates between the other end of the lever of the pile *c*. The screw is so adjusted that the pile occasions maximum current flow when the iron and rod 49 *b* are cold. As the iron heats up the pressure on the pile is reduced proportionately to the expansion of the thermostatic elements and consequently the current flow through the heater is proportionately reduced.

Another feature of my invention is that I provide means for directing articles issuing from between the roll 9 and the iron toward a table 71 located on the front or operator's side of the machine. As shown in Fig. 1, I provide an inclined table 72 immediately under the iron and the roll. As the articles leave the iron, they are directed by the inclination of this table toward the table 71 and therefore slide down the table 72 instead of piling up on it.

I also provide a table 73 on the frame 8 of the machine which is so located adjacent to the top of the roll when the roll is on the extreme position away from the iron. With this arrangement, the table 73 is conveniently located for adjusting articles to be ironed prior to the ironing when the roll is on the extreme position away from the iron. With this arrangement, the table 73 is conveniently located for adjusting articles to be ironed prior to the ironing operation as well as during the ironing operation.

Any suitable means may be employed for driving the roll operating mechanism. In the drawings, I have shown an electric motor 74 mounted on the frame 8 and belted 5 to a pulley 75 which is rigidly mounted on a drive shaft 76. The worm 14 is rigidly mounted on the driving shaft and, as previously described, operates continuously during the operation of the iron.

- 10 In operation, the operator starts the motor 74 after the burner 46 has been lighted and the iron is hot. Assuming that the roll 9 is in the extreme position away from the iron and that the cam bar 21 is in engagement with the notch 36 of the cam member 30, the motor will run idle since the clutches 16 and 19 are in the neutral or ineffective positions. After the articles to be ironed are adjusted in position with relation to the 15 roll 9 and the iron, the operator momentarily depresses the pedal 22, thereby rendering the clutch 19 effective and at the same time disengaging the bar 21 from the notch 36. The rotation of the cam member 30 swings the 20 roll 9 toward and into engagement with the iron and also prevents the cam bar from returning to the neutral position since the lateral face of the cam member holds the bar in such a position that the clutch 19 25 continues to be effective until the cam member has made a half revolution or has moved the slot 37 under the end of the cam bar 21. When this happens the cam bar in dropping into the slot 37 moves to the extreme position 30 in response to the pressure of the spring 25 and thereby disengages the clutch member 19 from its operative connection with the shaft 11 and renders the clutch 16 effective in transmitting power from the continuously 35 rotating worm wheel 15 to the driving gear 12 of the roll. During the half turn of the cam member, the bell cranks 32 at each end of the roller 9 have operated to move the roll 9 into engagement with the iron and to 40 subject the coil springs 33 to tensile strains. The roller is spring pressed against the iron and, if desired, means may be employed for adjusting the springs 33 for the purpose of varying the ironing pressure. A momentary 45 pressure on the pedal 22 will be effective in releasing the cam bar 21 from the slot 37, thereby stopping the rotation of the roll and causing the roll to swing away from the iron. 50

55 While I have illustrated but one embodiment

of my invention, it will be apparent to those skilled in the art that various changes and details of construction, modifications of parts and omissions or additions of elements may be made in the apparatus 60 illustrated without departing from the spirit and scope of the invention, as set forth by the appended claims.

I claim as my invention:

1. In combination, in an ironing machine, 65 an iron, a rotatable roll, a driven gear secured to said roll, pivoted members on which said roll is rotatively mounted, a driving gear meshing with said driven gear and coaxial with the pivotal axis of said pivoted 70 members, means including a rotatable element for swinging said roll about the pivotal axis of said pivot members toward and away from said iron, a rotatable driving shaft, means for selectively operatively coupling 75 said driving shaft to said rotatable element or to said driving gear, and means operable in accordance with the position of said rotatable element for controlling the operation of said coupling means. 80

2. In an ironing machine, the combination with a shoe and a roll to be moved to or from the shoe, of a shaft for the roll, a second shaft extending parallel to the roll, a support for each end of the roll shaft pivotally mounted on the second shaft, and means operated by the second shaft for impressing a displacing force upon the roll shaft to move the roll about the pivot points of the roll shaft supports. 85

3. In an ironing machine, the combination with a shoe and a roll member to cooperate with each other, of means for supporting one of said members, a motor for rotating the roll, a shaft extending parallel to the roll, an element thereon rotatable therewith for actuating the supporting means through bell-crank and springs, a double clutch on the shaft, one element of one clutch being secured thereto, a single member for controlling the double clutch to first rotate the shaft to actuate the supporting means to effect engagement of the roll and the shoe, and means then rendered operative to control the clutch to release the supporting 100 means and to connect the roll to the motor. 105

In testimony whereof, I have hereunto subscribed my name this 7th day of December, 1921.

EDWIN E. ARNOLD.
